DESIGN FOR A TOY CART

Verle C. Kenney, Chagrin Falls, Ohio

Application August 1, 1942, Serial No. 107,784

Term of patent 3½ years

To all whom it may concern:

Be it known that I, Verle C. Kenney, a citizen of the United States, residing at Chagrin Falls, in the county of Cuyahoga and State of Ohio, have invented a new, original, and ornamental Design for a Toy Cart, of which the following is a specification, reference being had to the accompanying drawing, forming part thereof.

In the drawing:

The figure is a perspective view of a toy cart showing my new design. The opposite side of the article is of the same appearance as the side shown.

I claim:

The ornamental design for a toy cart, substantially as shown and described.

VERLE C. KENNEY.
